12 Claims. (Cl. 250—93)

The present invention relates to an X-ray apparatus and particularly to X-ray apparatus in which the X-ray tube is arranged in a movable housing. X-ray apparatus of this type is usually connected to an alternating current supply circuit. The voltage of the alternating current circuit, however, is different at different points of consumption and may vary, for example, between the limits of 110 and 250 volts. To take care of this wide difference in voltage the primary winding of the transformer of the X-ray tube is provided with taps so that the supply circuit may be connected by means of an ordinary screw terminal to the particular one of the taps which corresponds to the normal voltage of the supply circuit at the place of installation of the X-ray apparatus, for example 110, 220 or 250 volts. In this manner, the X-ray apparatus is adjusted generally in accordance with the normal voltage of the supply circuit at the particular place of installation.

However, it is necessary to compensate for normal variations of the voltage of the supply circuit. If it is assumed that a supply circuit of 220 volts is connected to the 220 volt tap of the primary winding of the X-ray tube transformer, then if the voltage of the supply circuit would remain exactly constant at 220 volts, no further adjustment would be required. Supply circuits are ordinarily subject to permissible variations of voltage of 5% which, in reality, are usually doubled. In X-ray apparatus used for dental purposes, which is often connected to already overloaded circuits, these variations are frequently increased to 20% during the operation of the apparatus.

In order to compensate for these variations of the normal supply circuit voltage, it is common practice to connect a special auto transformer ahead of the conventional transformer, which converts the voltage of the alternating current source into the high voltage that is required for operation of the X-ray tube. These variations of voltage are compensated for by adjusting the auto transformer. The addition of the auto transformer, however, increases the cost of the X-ray apparatus, and the incorporation of the auto transformer requires an enlarged housing and, furthermore, increases the weight of the X-ray apparatus. This enlargement of the housing and increase in weight of the apparatus are of great disadvantage in apparatus used for dental purposes since the operator must frequently adjust the X-ray apparatus that is suspended from a standard.

An important object of the present invention is to eliminate the necessity for the use of a device separate from the main transformer, that is used to energize the X-ray tube, for compensating for slight variations in line voltage which are undesirable in operating the X-ray tube. 5

Another important object of the invention is to provide for adjusting the connection of the primary winding of a transformer, that is connected to energize an X-ray tube, to an alternating current circuit in a plurality of small steps to compensate for variations in the voltage of the alternating current circuit. 10

An object of the invention is to incorporate in an X-ray tube housing that is movably mounted, such as for use by a dentist, the transformer for energizing the X-ray tube together with a simple and readily adjustable means for compensating for slight variations in line voltage which requires a minimum of space and has little weight. 15

Other objects of the invention will, in part, be obvious and in part appear hereinafter.

The invention, accordingly, is disclosed in the embodiment hereof shown in the accompanying drawings, and it comprises the features of construction, combination of elements and arrangement of parts which will be exemplified in the construction hereinafter set forth, and the scope of the application of which will be indicated in 25 the appended claims. 30

For a more complete understanding of the nature and scope of the invention, reference may be had to the following detailed description taken in connection with the accompanying drawings, in 35 which:

Figure 1 is a view, in side elevation, of the X-ray apparatus;

Figure 2 is a view at an enlarged scale of a portion of the X-ray apparatus shown in Figure 40 1, certain parts being broken away to more clearly illustrate the invention;

Figure 3 is a sectional view taken along the line 3—3 of Figure 2;

Figure 4 is a perspective view, on an enlarged 45 scale, showing the arrangement of the gear wheels that are employed in adjusting the taps on the primary winding of the transformer;

Figure 5 is a detail sectional view taken along the line 5—5 of Figure 4; 50

Figure 6 is a perspective view of the adjusting ring; and

Figure 7 illustrates, diagrammatically, the circuit connections that may be employed in practicing the present invention. 55

In order to avoid the foregoing described disadvantages, a group of taps is provided on the primary winding of the X-ray tube transformer, in accordance with the present invention, with at least one manually operated adjusting member controlling a regulating device by means of which one terminal of the circuit may be selectively connected to each of the single taps of the group. This arrangement eliminates the necessity for a separate auto transformer since the differences in the voltage of the supply circuit may be taken care of by corresponding adjustment of the regulating device through the operation of the manual adjusting member. In this manner, an increase in the size of the X-ray apparatus housing is unnecessary, as is otherwise the case when a separate auto transformer is employed, and at the same time there is a corresponding decrease in the weight of the apparatus.

Referring now to the drawings, it will be observed that the lower portion 1 (Figure 1) of the housing 2 is provided for carrying the X-ray tube 3 (Figure 7) and that a tubus 4 extends therefrom. In the upper portion 5 of the housing 2 the transformer, shown generally at 6 in Figure 7, is mounted having a primary winding 7 and a secondary winding 8. The transformer 6 is immersed in oil which is contained within the upper portion 5 of the housing 2. Conductors 9 and 10 lead in a well known manner from the secondary winding 8 to the cathode of the X-ray tube 3 while the conductor 11 leads from the secondary winding 8 to the anode of the tube 3.

The upper portion 5 of the housing 2 is provided on top with a tubular section 12. A flanged member 13 of a plug 15, having a central bore 14 is secured to this tubular stud by means of screws 16. A flange 17 is provided at the lower portion of the hollow plug 15. A cylindrical portion 18, serving as a supporting element, is provided between the two flanges 13 and 17. By means of the supporting element 18 of the hollow plug 15, the entire housing 2 is rotatably mounted in a well known manner upon a standard (not shown) so that the housing 2 and apparatus contained therein may be pivoted about the axis of the hollow plug 15.

In the lower portion of the hollow space 19, Figure 2, of the tubular section 12, an insulating disc 20 is secured which engages with its offset portion 21 an internal flange 22 of the tubular section 12. The insulating disc 20 is provided with a recess 23 that is open at the top and is defined at the bottom by a bottom plate portion 24. The hollow space 19 is closed off from the upper portion 5 of the housing that is filled with oil by means of the insulating disc 20. The bottom plate portion 24 of the insulating disc 20 is provided with a ring of, for example, nine contact members 25 that are connected by means of ordinary screw terminals 67 with nine taps 7a to 7i at the left hand end of the primary winding 7 of the transformer 6, as viewed in Figure 7, by means of separate conductors 26. The taps 7a to 7i provide for compensating for slight differences of voltage, for example, differences between 200 volts and 240 volts.

A sheet metal mounting plate 27, shown more clearly in Figure 4, is secured to the flange 22 by means of screws which extend through holes 28 in this plate. A shaft 29 of insulating material, such as hard rubber, is mounted upon the plate 27, coaxially with the above described plug 15. Above plate 27 a gear wheel 30 is secured to the insulating shaft 29. The portion of the shaft

29 extending below the plate 27 is rigidly connected with a metal stud 31 that is rotatably arranged upon a contact member 32 which is stationarily mounted in the bottom portion 24 of the disc 20. The contact member 32 is connected by a conductor 33 with a terminal member 34 that is positioned outside of the ring of contact members 25 which are mounted on the insulating disc 20.

A conductor 35, extending through bore 14, Figure 2, leads from the terminal member 34 to one slip ring 37 of three slip rings 36, 37 and 38 which are provided at the upper portion of the hollow plug 15. The slip rings 36, 37 and 38 are insulated from each other by insulating rings 39 and they are also insulated from the flange 17 of the plug 15. A conductor 40, extending through bore 14, leads from the slip ring 36 to a second terminal member 41 that is disposed outside of the ring of contact members 25 on the insulating disc 20 and which is connected by means of a conductor 42 and the described terminals 67 to one or the other of the two taps 7k or 7m at the right hand end of the primary winding 7, as viewed in Figure 7.

The conductor 42 is connected to either tap 7k or 7m depending upon the voltage of the supply circuit at the place of installation of the X-ray apparatus. If the voltage of the supply circuit is 220 volts, the conductor 42 is connected to tap 7k. If the normal voltage of the supply circuit is 250 volts, then conductor 42 is connected to tap 7m. If desired, a plurality of taps may be provided at the right hand end of the primary winding 7 in order to permit connection of the conductor 42 to a tap of the primary winding corresponding to other supply circuit voltages, such as a voltage 110 volts.

From the slip ring 38 a conductor 43, extending through bore 14, leads to a third terminal member 44 that is positioned outside of the ring of contact members 25 on the insulating disc 20. The terminal member 44 is connected by a conductor 45 to one terminal of a milliammeter 68 connected between the two halves of the secondary winding 8. The purpose of the three slip rings 36, 37 and 38 will be described in more detail hereinafter. The terminal members 34, 41 and 44 also form screw terminals to permit easy connection of the conductors described hereinbefore thereto. In the circuit diagram shown in Figure 7 of the drawings, the conductors 35, 40 and 43 are externally connected to the slip rings 36, 37, and 38 to more clearly illustrate the invention.

A contact arm 46 is carried by the metal stud 31 and rotates with the shaft 29. As shown, it is provided with a spring pressed sliding contact member 47. When the arm 46 swings about the axis of the shaft 29, the sliding contact member 46 comes successively into contact engagement with the contact members 25 that are carried by the insulating disc 20.

A stud 48 is mounted on the plate 27, Figure 4, for rotatably mounting a gear wheel 49. The gear wheel 49 meshes with gear wheel 30 and also with teeth 50 that are provided on the inner periphery of a manually operated adjusting ring 51, Figure 6. The adjusting ring 51 is rotatably mounted within a recess 52 that is provided near the upper end of the tubular section 12. In order to effect engagement of the gear wheel 49 with the teeth 50, a recess 53, Figure 3, is provided at the upper end thereof. A positioning ball 55 is movably mounted in a cross-bore 54 and a

spring 56 biases the ball 55 into engagement with one of a plurality of notches 57 in the inner periphery of the adjusting ring 51, depending upon its position. A stop 58 is mounted on the 5 tubular section 12 for engaging the ends of a recess 59 in the adjusting ring 51, thereby limiting its rotation in either direction.

Referring particularly to Figure 6 of the drawings, it will be observed that numerals 1 through 10 9 are indicated upon the outer surface of the adjusting ring 51 to permit a definite setting thereof with respect to an index marking 60 on flange 13, Figure 1. The numerals through 9 correspond to the nine contact members 25 and to 15 the notches 57.

The three rings 36, 37 and 38, which are arranged above the support section 18, cooperate with contact fingers 61, 62 and 63 respectively. These contact fingers are arranged in the standard (not shown) that carries the X-ray apparatus. The contact fingers 61 and 62 are connected by conductors 64 and 65, respectively, with the terminals of the alternating current supply circuit while the contact finger 63 is connected 25 to ground by a conductor 66.

In describing the operation of the invention herein disclosed it will be assumed that a normal alternating current supply circuit voltage of 220 volts is available at the place where the 30 X-ray apparatus is installed. The conductor 42 is then connected to tap 7k and the adjusting ring 51 is positioned so that the contact member 47 carried by the arm 46 engages the fifth contact member 25 or that contact member numbered 5 in Figure 7 of the drawings. This adjustment of the parts corresponds to the operation of the X-ray apparatus when a normal supply circuit voltage of 220 volts is available. The circuit may be traced from conductor 65 through contact finger 62, slip ring 37, conductor 35, terminal member 34, conductor 33, contact 32, Figure 5, contact arm 46, fifth contact member 25, corresponding conductor 26, tap 7e, a portion of the primary winding 7 between the tap 7e and the tap 7k, conductor 42, terminal member 41, conductor 40, slip ring 36, contact finger 61, to conductor 64.

If the voltage of the supply circuit is higher than normal, such as is the case before and after peak periods of the day, the contact arm 46 is 50 moved by means of the adjusting ring 51 from the fifth position in a counterclockwise direction, as viewed in Figure 7. That is, the movement is in the direction of the first contact member 25 so that the circuit is connected successively to 55 taps 7d, 7c, 7b and 7a. The contact arm 46 is rotated until the voltmeter (not shown) of the X-ray apparatus indicates that the increase of voltage of the supply circuit has been compensated for or the milliammeter 68 in the secondary circuit shows the number of milliamperes for 60 which the machine has been adjusted. If, however, the voltage of the supply circuit falls below its normal value, as is the case on overloaded circuits, the contact arm 46 is rotated clockwise 65 from the fifth position, as viewed in Figure 7 so that the circuit is connected successively to taps 7f, 7g, 7h and 7i. In this manner differences of 70 10% above and below the normal voltage of the supply circuit may be compensated for. A total range of 20% compensation is thus provided. The taps can be arranged so that any percentage of voltage variations can be compensated for. This insures that the X-ray tube 75 3 operates at all times under constant voltage

conditions. For example, if the X-ray tube 3 normally requires a voltage of 45,000 volts, a difference of 10% in the voltage applied to the primary winding 7 would cause a difference of 4500 volts in the voltage applied by the secondary winding 8 to the X-ray tube 3, thereby greatly impairing the effectiveness of the X-ray tube and the sharpness of the X-ray picture. When the regulating device disclosed herein is employed to compensate for slight variations in circuit voltage the technique of exposure is standardized and pictures of uniform characteristics are obtained.

The foregoing described construction in which the circuit may be selectively connected to different taps of the primary winding of an X-ray transformer by means of a manually controlled regulating device may be applied to X-ray apparatus of many different kinds. In the embodiment disclosed herein the tap changing apparatus is built into an X-ray apparatus in which the transformer only is surrounded by oil. It will be understood that this apparatus may also be applied to an X-ray apparatus in which the transformer as well as the X-ray tube are completely surrounded by oil. Instead of employing the herein described regulating device in which a contact arm is moved over a ring of contact members by means of an adjusting ring, regulating devices of a different type may be employed. 20 The circuit may be connected to different taps on the primary winding by means of a button regulator that is similar to the button regulators employed in dental apparatus which would be mounted upon the housing that contains the 25 transformer and the X-ray tube.

Since certain further changes may be made in the above construction and different embodiments of the invention may be made without departing from the scope thereof, it is intended 40 that all matter contained in the above description or shown in the accompanying drawings shall be interpreted as illustrative and not in a limiting sense.

I claim as my invention:

1. X-ray apparatus comprising, in combination, a housing disposed to be movably mounted, an X-ray tube mounted in said housing, a transformer mounted in said housing having a secondary winding connected to said X-ray tube and a primary winding for connection to an alternating current circuit having a normal operating voltage, a plurality of taps on said primary winding, and a tap changing switch mounted in said housing and arranged and adapted to selectively connect said taps to said circuit in such manner as to cause said secondary winding to apply a predetermined voltage to said X-ray tube on slight change of the circuit voltage from said normal operating voltage as applied to said 50 primary winding.

2. X-ray apparatus comprising, in combination, a housing disposed to be movably mounted, an X-ray tube mounted in said housing, a transformer mounted in said housing having a secondary winding connected to said X-ray tube and a primary winding for connection to an alternating current circuit having a normal operating voltage, a plurality of taps on said primary winding, a tap changing switch mounted in said 65 housing and arranged and adapted to selectively connect said taps to said circuit in such manner as to cause said secondary winding to apply a predetermined voltage to said X-ray tube on slight change of the circuit voltage from said 70 75

normal operating voltage as applied to said primary winding, and externally operable means carried by said housing and operatively connected to said tap changing switch for operating the 5 same.

3. In X-ray apparatus, a housing disposed to be rotatably mounted, a plurality of stationary contact members arranged in a circle in said housing, a contact arm rotatably mounted in 10 said housing for successively engaging said contact members, and rotatable adjustment means operatively connected to said contact arm and adapted to be moved exteriorly of and relative to said housing for rotating said contact arm, 15 the axis of rotation of said adjusting means being coincident with the axis of rotation of said housing.

4. In X-ray apparatus, a housing disposed to be rotatably mounted, a plurality of stationary 20 contact members arranged in a circle in said housing, a contact arm rotatably mounted in said housing for successively engaging said contact members, rotatable adjusting means operatively connected to said contact arm and adapted to be moved exteriorly of and relative to said 25 housing for rotating said contact arm, the axis of rotation of said adjusting means being coincident with the axis of rotation of said housing, and means causing said adjusting means to be stopped at positions corresponding to the various 30 positions of said contact arm in individual engagement with said contact members.

5. In X-ray apparatus, a housing disposed to be rotatably mounted, a plurality of stationary 35 contact members arranged in a circle in said housing, a contact arm rotatably mounted in said housing for successively engaging said contact members, rotatable adjusting means operatively connected to said contact arm and adapted to be moved exteriorly of and relative to said 40 housing for rotating said contact arm, the axis of rotation of said adjusting means being coincident with the axis of rotation of said housing, means causing said adjusting means to be stopped at positions corresponding to the various 45 positions of said contact arm in individual engagement with said contact members, and stop means limiting the rotation of said adjusting means in either direction.

50 6. In X-ray apparatus, a housing disposed to be movably mounted, a plurality of stationary contact members arranged in a circle in said housing, a contact arm rotatably mounted in said housing for successively engaging said contact members, a gear wheel mounted in said housing for rotation with said contact arm, and an adjusting ring rotatably mounted on said 55 housing and having teeth on its inner periphery for driving said gear wheel and adapted to be moved exteriorly of said housing for rotating said contact arm.

65 7. In X-ray apparatus, a housing disposed to be movably mounted, a plurality of stationary contact members arranged in a circle in said housing, a contact arm rotatably mounted in said housing for successively engaging said contact members, a gear wheel mounted in said housing for rotation with said contact arm, an 70 adjusting ring rotatably mounted on said housing and having teeth on its inner periphery for driving said gear wheel and adapted to be moved exteriorly of said housing for rotating said contact arm, and spring biased means co-operating with said adjusting ring and tending 75

to stop the same at positions corresponding to the various positions of said contact arm in engagement with each of said contact members.

8. In X-ray apparatus, a housing disposed to be movably mounted, a plurality of stationary 5 contact members arranged in a circle in said housing, a contact arm rotatably mounted in said housing for successively engaging said contact members, a gear wheel mounted in said housing for rotation with said contact arm, an 10 idler gear wheel meshing with said gear wheel, an adjusting ring rotatably mounted on said housing having teeth extending inwardly along a portion of its inner periphery and meshing with said idler gear wheel and having spaced recesses along another portion of its inner periphery each corresponding to one of said contact members, said adjusting ring being movable exteriorly of said housing, and a spring pressed member disposed to cooperate with said recesses for stopping said adjusting ring at positions corresponding to various positions of said contact arm in individual engagement with said contact members. 15

9. In X-ray apparatus, a housing disposed to 20 be movably mounted, a plurality of stationary contact members arranged in a circle in said housing, a contact arm rotatably mounted in said housing for successively engaging said contact members, a gear wheel mounted in said 25 housing for rotation with said contact arm, an idler gear wheel meshing with said gear wheel, an adjusting ring rotatably mounted on said housing having teeth extending inwardly along a portion of its inner periphery and meshing with 30 said idler gear wheel and having spaced recesses along another portion of its inner periphery each corresponding to one of said contact members, said adjusting ring being movable exteriorly of said housing, a spring pressed member disposed 35 to cooperate with said recesses for stopping said adjusting ring at positions corresponding to various positions of said contact arm in individual engagement with said contact members, and stop means cooperating with said adjusting ring for 40 definitely limiting the rotation thereof in either direction. 45

10. X-ray apparatus comprising, in combination, a housing disposed to be movably mounted, an X-ray tube mounted in said housing, a transformer mounted in said housing having a secondary winding connected to said X-ray tube and a primary winding for connection to an alternating current circuit having a normal operating voltage, a plurality of taps on said primary winding, 55 a plurality of stationary contact members arranged in a circle in said housing and each connected to one of said taps, a contact arm rotatably mounted in said housing for successively engaging said contact members to selectively connect said taps to said circuit in such manner as to cause said secondary winding to apply a pre-determined voltage to said X-ray tube on slight changes of the circuit voltage from said normal operating voltage as applied to said primary 60 winding, and a rotatable adjusting ring operatively connected to said contact arm and adapted to be moved exteriorly of said housing for rotating said contact arm. 65

11. X-ray apparatus comprising, in combination, 70 a housing disposed to be movably mounted, an X-ray tube mounted in said housing, a transformer mounted in said housing having a secondary winding connected to said X-ray tube and a primary winding for connection to an al- 75

ternating current circuit having a normal operating voltage, a plurality of taps on said primary winding, a plurality of stationary contact members arranged in a circle in said housing and each connected to one of said taps, a contact arm rotatably mounted in said housing for successively engaging said contact members to selectively connect said taps to said circuit in such manner as to cause said secondary winding to apply a predetermined voltage to said X-ray tube on slight changes of the circuit voltage from said normal operating voltage as applied to said primary winding, a rotatable adjusting ring operatively connected to said contact arm and adapted to be moved exteriorly of said housing for rotating said contact arm, and means tending to stop said adjusting ring at positions corresponding to the various positions of said contact arm in individual engagement with said contact members.

12. X-ray apparatus comprising, in combination, a housing disposed to be movably mounted, an X-ray tube mounted in said housing, a transformer mounted in said housing having a secondary winding connected to said X-ray tube and a primary winding for connection to an alternating current circuit having a normal operating volt-

age, a plurality of taps on said primary winding, a plurality of stationary contact members arranged in a circle in said housing and each connected to one of said taps, a contact arm rotatably mounted in said housing for successively 5 engaging said contact members to selectively connect said taps to said circuit in such manner as to cause said secondary winding to apply a predetermined voltage to said X-ray tube on slight changes of the circuit voltage from said normal 10 operating voltage as applied to said primary winding, a gear wheel mounted in said housing for rotation with said contact arm, an idler gear wheel meshing with said gear wheel, an adjusting ring rotatably mounted on said housing having 15 teeth extending inwardly along a portion of its inner periphery and meshing with said idler gear wheel and having spaced recesses along another portion of its inner periphery each corresponding to one of said contact members, said adjusting 20 ring being movable exteriorly of said housing, and a spring pressed member disposed to cooperate with said recesses for stopping said adjusting ring at positions corresponding to various 25 positions of said contact arm in individual engagement with said contact members.

EDWARD J. RIES.

CERTIFICATE OF CORRECTION.

Patent No. 2,140,393.

December 13, 1938.

EDWARD J. RIES.

It is hereby certified that error appears in the above numbered patent requiring correction as follows: In the heading to the drawings, line 3, for the filing date "Nov. 3, 1937" read May 3, 1937; and in the printed specification, page 4, first column, line 11, claim 3, for the word "adjustment" read adjusting; and that the said Letters Patent should be read with this correction therein that the same may conform to the record of the case in the Patent Office.

Signed and sealed this 31st day of January, A. D. 1939.

Henry Van Arsdale

(Seal)

Acting Commissioner of Patents.
